(57) **CLAIM**

The ornamental design for a display screen or portion thereof with animated graphical user interface as shown and described.

DESCRIPTION

FIG. 1 is a front view of a first image in a sequence of a display screen or portion thereof with animated graphical user interface showing our new design;

FIG. 2 is a front view of the second image thereof; and, FIG. 3 is a front view of the third image thereof.

The appearance of the image transitions sequentially between the images shown in FIG. 1-3 of the display screen or portion thereof with animated graphical user interface. The dot-dash broken line illustrates a display screen or portion thereof and forms no part of the claimed design. The even-dash broken lines illustrate portions of the animated graphical user interface that form no part of the claimed design. The grayscale fill in the drawings indicates a contrast in appearance.
